UNITED STATES PATENT OFFICE.

JOSEPH LAUTENBURG, OF NEW YORK, N. Y.

RETAINING MEANS FOR SETS OF TEETH.

1,091,852.

Specification of Letters Patent. Patented Mar. 31, 1914.

Application filed June 3, 1913. Serial No. 771,438.

To all whom it may concern:

Be it known that I, JOSEPH LAUTENBURG, a citizen of the United States, residing at No. 270 Grand street, in the city of New York, in the county of New York and State of New York, have invented a new and useful Retaining Means for Sets of Teeth, of which the following is a specification.

My invention relates to improvements in means for retaining sets of artificial teeth, and it consists in the novel features herein-after more fully described.

The objects of my improvement are:— First, to provide an effective means for retaining sets of artificial teeth in place. Second, to render the wearing of the sets as comfortable as possible, and to prevent the rubbing or scratching of the inside of the mouth by the coils or wires of any springs or by sharp edges of any sort. Third, to reduce the size of the upper plate, and fourth, to have the said retaining means simple, durable and comparatively inexpensive. I attain these objects by the device illustrated in the accompanying drawings or by any equivalent modification of the same.

In the drawings Figure 1 is an elevation of two sets of upper and lower teeth respectively, showing my retaining means in position, but quite larger than would be made in practice. Fig. 2 is a plan or top view of the lower set of teeth and of the lower half of my retaining means, shown as cut by a plane passing through the line A B of Fig. 1. Fig. 3 is a sectional elevation of my retaining means on a large scale, showing the inner working parts of the same. Fig. 4 shows a modification of my retaining means containing a single series of telescoping tubes shown in elevation. Fig. 5 is an elevation of another modification of my retaining means having a double series of telescoping tubes decreasing in size from the middle toward the ends; a modified form of the universal joint 12 is also shown at the upper end of Fig. 5. Fig. 6 is an outer end view of Fig. 5, without the universal joint. Fig. 7 is an outer end view of Fig. 3. Fig. 8 is a detail of the pin 11 of Fig. 1, showing one method of holding in place the universal joint, which is not shown in Fig. 8. Fig. 9 shows another method of securing the pin 11 to the universal joint 12, which is shown with its longer side horizontal.

Similar numerals refer to similar parts throughout the several views of the drawings, as follows: 10, 10, are anchors or extensions of the pins 11, 11, embedded in the gums 60 of the upper and lower sets of teeth.

12, 12, are universal joints shown in Fig. 1 as connecting the pins 11, 11, to the ends of the series of telescoping tubes 14, 14, 15, 15 and 16, forming a shell of variable 65 length; 13, 13 are the lugs or ears at the ends of the tubes 14, 14, by means of which these are connected to said universal joints 12, 12.

17, 17, are two compression springs shown 70 in Fig. 3 as abutting at their inner ends against the middle partition 24 of the tube 16 and at their outer ends against the heads 20, 20, shown as screwed into the outer ends of the tubes 14, 14. 23, 23, are annular 75 grooves in the inner faces of said heads 20, 20, which grooves are adapted to receive the outer ends of said spring 17, 17.

18 and 19 are additional tubes in the single telescoping series or shell shown in Fig. 80 4: the tube 16 at the smaller end of this series is shown as having lugs 13 similar to those carried by tube 14.

21, 21, are rivet heads at the ends of the pins 11, 11, shown in Figs. 1, 5 and 9 as 85 holding the universal joints 12, 12 in place.

22 is the head of a set-screw shown in Fig. 8 as secured to the pin 11, which has an opening with a female thread to receive it, and which head 22 could serve the same 90 purpose as the rivet head 21 of Figs. 1, 5 and 9.

All the parts of my device could be made of any suitable material, and the operation of the same is evident from the drawings. 95

I prefer to have the ends of my retaining means secured to the upper set of teeth between the second upper bicuspid and the first molar, and to the lower set near the first molar tooth.

The shell or telescoping series of tubes is intended to protect the inside of the mouth from rubbing or scratching by the springs 17, 17, and the outer edges of these tubes are shown in the drawings as carefully rounded off.

Fig. 2 shows my retaining means as located on the outer side of the teeth, namely, between the gum and the cheek; but they could also be placed inside of the set 110 of teeth, *i. e.* between the teeth and the tongue; they could also be placed in line

with the teeth, some of the pins 11, 11, being then replaced each by a vertical eye or lug, similar to the lugs 13, 13, and secured to the gums by means of anchors 10, 10, or in any other suitable manner. These eyes or lugs could be secured to a universal joint of a form shown in Fig. 5 by means of pins 11, 11, held in place by rivet heads 21, 21, at each end; one of the teeth in each set 15 may then be omitted, or it may be made hollow to receive the ends of my retaining device.

Either one or both universal joints may be omitted, if the telescoping tubes be loose 15 enough to permit some lateral flexibility.

My retaining means can also be applied to one set of the teeth only by connecting one end of each telescoping series or shell to a band or cap secured to a tooth on each 20 side of the opposite jaw.

The telescoping tubes may be made curved instead of straight as in the drawings, and they may be oblong in cross-sec-

tion, instead of being round as shown; the springs 17, 17, may be made different in 25 shape, and one spring may be used instead of two; the forms of all the details and connections of my retaining means may also be varied considerably. Compressed air may also be used instead of springs, if desired. 30

Many other modifications could be made in my retaining means without departing from the main scope of my invention.

What I claim as my invention, and desire to secure by Letters Patent, is—

In a retaining means for a set or sets of teeth a series of multiple telescoping shells inclosing an elastic medium tending to separate said sets of teeth and comprising one or more intermediate shells and terminal 40 shells connected at their ends to said sets of teeth.

JOSEPH LAUTENBURG.
